(57) **CLAIM**

The ornamental design for a headset, as shown and described.

DESCRIPTION

FIG. 1 is a left side view of a headset showing our design according to a first embodiment;

FIG. 2 is a right side view thereof;

FIG. 3 is a front view thereof;

FIG. 4 is a back view thereof;

FIG. 5 is a top view thereof;

FIG. 6 is a bottom view thereof;

FIG. 7 is a front right perspective view thereof;

FIG. 8 is a back right perspective view thereof;

FIG. 9 is a back left perspective view thereof; and,

FIG. 10 is a front left perspective view thereof.

The even-length broken lines are directed to environment, represent unclaimed subject matter, and form no part of the claimed design.
